DESIGN FOR A BASEBALL TARGET GAME

William C. Otto, New York, N. Y.

Application September 18, 1935, Serial No. 58,614

Term of patent 3½ years

To all whom it may concern:

Be it known that I, William C. Otto, a citizen of the United States, residing at New York city, in the county of New York and State of New York, have invented a new, original, and ornamental Design for Baseball Target Games, of which the following is a specification, reference being had to the accompanying drawing, forming a part thereof.

Fig. 1 is a top plan view of a baseball target game showing my new design.

Fig. 2 is an edge view looking in the direction of the arrows of line 2—2 of Fig. 1.

Fig. 3 is an edge view looking in the direction of the arrows of line 3—3 of Fig. 1.

I claim:

The ornamental design for a baseball target game as shown.

In testimony whereof I have affixed my signature.

WILLIAM C. OTTO.
